UNITED STATES PATENT OFFICE.

ERNEST CLEFF, OF NEW YORK, N. Y., ASSIGNOR TO THE SPRINGFIELD METALLIC CASKET COMPANY, OF SPRINGFIELD, OHIO, A CORPORATION OF OHIO.

DESIGN FOR A PLATE AND HANDLE FOR CASKETS.

No. 38,328.

Specification for Design.

Patented Nov. 27, 1906.

Application filed July 9, 1906. Serial No. 325,418. Term of patent 7 years.

To all whom it may concern:

Be it known that I, ERNEST CLEFF, a citizen of the United States, residing at New York, in the county of New York and State of New York, have invented a new, original, and ornamental Design in Plates and Handles for Caskets, of which the following is a specification.

My invention relates to a new, original, and ornamental design for plates and handles for caskets.

The accompanying drawing is a plan view of such a plate and handle embodying my design.

I claim—

The ornamental design for a plate and handle for caskets, as shown.

ERNEST CLEFF.
